UNITED STATES PATENT OFFICE.

JOHN D. ADAMS, OF NEW YORK, N. Y.

DESIGN FOR A BADGE.

SPECIFICATION forming part of Design No. 25,499, dated May 19, 1896.

Application filed February 18, 1896. Serial No. 579,799. Term of patent 14 years.

To all whom it may concern:

Be it known that I, JOHN D. ADAMS, a citizen of the United States, residing in the city and county of New York, State of New York, have invented a new and useful Design for Society Badges, of which the following is a specification.

This invention relates to a society badge of peculiar shape and arrangement and ornamentation, composed of the Greek letters "Chi" and "Phi;" and I do hereby declare that the drawing accompanying this specification conveys to any one a clear understanding of the invention and is sufficient to enable 15 such person to use the same.

The letter "Chi" is arranged above the letter "Phi," with the cross-bar of the "Phi" extending above the top and beneath the base of the "Chi." This cross-bar at its top and 20 bottom has recesses *a* and *b*, and the inner

lateral projections *a' b'* of the "Chi" at the top and bottom come opposite the recesses *a* and *b*, respectively. This characterizes the shape and arrangement of the letters.

The ornamentation of the badge is characterized by stemwork extending along the cross-bars of the "Chi" and having bunches of grapes and leaves.

What I claim as new, and desire to secure by Letters Patent, is—

The design for a badge, substantially as shown and described.

In testimony whereof I have signed my name to this specification in the presence of two subscribing witnesses.

JOHN D. ADAMS.
